ABSTRACT: New compounds corresponding to the formula:

in which R_1 and R_2 are, independently, hydrogen, lower alkyl, allyl, and cycloalkyl having from three to six carbon atoms, inclusive; X is halogen or lower alkyl having one to four carbon atoms, inclusive; and n is an integer having a value from 0 to 4, inclusive. The above compounds are effective herbicides, particularly for the control of grasses and broadleaf plants, with both preemergence and post-emergence activity. Representative compounds are: glyoxylanilideoximino-N'-allyl carbamate, glyoxylanilideoximino-N'-n-butyl carbamate, glyoxyl-3,4-dichloroanilideoximino-N'-methyl carbamate, and glyoxylanilideoximino-N'-n-propyl carbamate.

GLYOXYLANILIDEOXIMINO CARBAMATES

This invention relates to novel compounds useful as active herbicidal substances. More specifically, this invention relates to a novel type of glyoxylanilideoximino carbamates and their use as effective herbicides.

The novel compounds of the present invention correspond to the formula:

in which R₁ and R₂ are independently selected from the group consisting of hydrogen, lower alkyl, allyl and cycloalkyl having from three to six carbon atoms, inclusive; X is selected from the group consisting of halogen and lower alkyl having one to four carbon atoms, inclusive; and n is an integer having a value from 0 to 4, inclusive.

The method of the present invention of controlling undesirable vegetation comprises applying an herbicidally effective amount of the above represented compounds to the area where control is desired.

The term lower alkyl, unless otherwise defined, preferably includes those members of the group which contain from one to about six carbon atoms, inclusive, in both straight chain and branched chain configurations. The term halogen preferably includes fluorine, chlorine and bromine. X_n preferably includes mono-, di-, tri-, and tetra- substitution on the phenyl ring. For example, monochlorophenyl, dichlorophenyl, trichlorophenyl and tetrachlorophenyl, similarly dichlorodimethylphenyl, trifluoromonomethylphenyl and the like.

The following table is exemplary of compounds of this invention.

TABLE I

Compound Number	X _n	R ₁	R ₂	M.P. ° C. or np ¹⁰
1	Hydrogen	Methyl		62° (decomposition).
2	do	Allyl		(Semi-solid).
3	do	n-Butyl		Do.
4	3-chloro-4-methyl	do	Methyl	105-6° (decomposition).
5	3,4-dichloro	do	do	101-3° (decomposition).
6	do	do	Allyl	129-129.5° (Viscous oil).
7	2,4-dimethyl	do	n-Butyl	70-71°.
8	do	do	Methyl	176-178°.
9	do	do	Cyclohexyl	109-110°.
10	do	do	i-Propyl	1.6466.
11	do	do	n-Propyl	

X _n	R ₁	R ₂
Hydrogen	Methyl	
do	Allyl	
do	n-Butyl	
do	Methyl	
3-chloro, 4-methyl	do	do
3, 4-dichloro	do	Allyl
do	do	Allyl
2, 4-dimethyl	do	n-Butyl
do	do	Methyl
do	do	Cyclohexyl
do	do	i-Propyl
do	do	n-Propyl
4-ethyl	do	Methyl
do	do	Cyclopropyl
3, 4-dibromo	do	Allyl
Methyl	Methyl	Hydrogen
3-chloro	n-Propyl	Methyl
4-sec-butyl	Allyl	do
Methyl	Hydrogen	n-Hexyl
4-fluoro	Methyl	Methyl
3, 4-dichloro	Cyclobutyl	Allyl
	Cyclopropyl	Methyl

The novel class of compounds of this invention are prepared by one of several general methods. One such general method is the condensation between an appropriate isocyanate or carbamoyl chloride and an appropriate glyoxylanilide oxime. The reaction proceeds readily in the liquid phase. The employment of a solvent also is useful in facilitating processing, as well as aiding during the agitation and mixing of the reactants. A catalyst may be employed to enhance the reaction. No catalyst is required. Such catalysts as di-n-butylin dilaurate or triethylamine are effective catalysts. The reactions preferably are carried out at temperatures that permit operation in the liquid phase. These temperatures are between about room temperature and reflux temperature of the solvent, if one is employed.

15 The following examples are presented to show how certain specific compounds of the invention are prepared and to illustrate the effectiveness of certain compounds of the invention as herbicides.

20

EXAMPLE I

Preparation of glyoxylanilideoximino-N' methyl carbamate.

Glyoxylanilide oxime, 6.0 g. (0.036 m.) is partially dissolved in 25 ml. of acetone. A slight excess of methyl isocyanate is 25 added along with three drops of dibutyltin dilaurate. After approximately a 10 minute reaction induction period the temperature autogenously increased from room temperature to 35° C. During this period the solution becomes clear. The product crystallizes out of solution at room temperature. A second crop of crystals is collected by adding hexane. There is obtained 7.0 g. of the title compound, m.p. at 62° C. with decomposition. The identity of the product was confirmed by elemental analysis: Calculated: Carbon, 54.3 percent, H, 4.95 percent. Found: Carbon, 54.13 percent, H, 4.84 percent.

30 35 The following table, table II, is a listing of compounds which are similarly prepared in accordance with the above given example. Compound numbers have been assigned to them and are used for identification throughout the balance of the specification.

TABLE II

HERBICIDAL SCREENING TESTS

60 60 As previously mentioned, the herein described new compositions produced in the above described manner are phytotoxic compounds which are useful and valuable in controlling various plant species. Compounds of this invention are tested as herbicides in the following manner.

65 Preemergence herbicide test:

On the day preceding treatment, seeds of seven different weed species are planted in individual rows using one species per row across the width of the flat. The seeds used are hairy crabgrass (*Digitaria sanguinalis* (L.) Scop.), yellow foxtail, 70 (*Setaria Glauca* (L.) Beauv.), watergrass (*Echinochloa crusgalli* (L.) Beauv.), wild oats (*Avena fatua* L.), redroot pigweed (*Amaranthus retroflexus*, (L.), Indian mustard (*Brassica juncea* (L.) Coss.) and curly dock (*Rumex crispus*, (L.). Ample seeds are planted to give about 20 to 50 seedlings per row, depending on the size of the plants. The flats are watered

after planting. The following day each flat is sprayed at the rate of 20 pounds of the candidate compound per 80 gallons of solution per acre. An atomizer is used to spray the solution on the soil surface. The flats are placed in a greenhouse at 80° F. and watered regularly. Two weeks later the degree of weed control is determined by comparing the amount of germination and growth of each weed in the treated flats with weeds in several untreated control flats. The rating system is as follows:

- no significant injury (0-15 percent control)
- += slight injury (25-35 percent control)
- ++= moderate injury (55-65 percent control)
- +++= severe injury or death (85-100 percent control)

An activity index is used to represent the total activity on all seven weed species. It is the sum of the number of plus marks, so that an activity index of 21 represents complete control of all seven weeds. The results of this test are reported in table II. Postemergence Herbicide Test:

Seeds of five weed species including hairy crabgrass, watergrass, wild oats, Indian mustard, and curly dock and one crop pinto beans (*Phaseolus vulgaris*), are planted in flats as described above for preemergence screening. The flats are placed in the greenhouse at 72°-85° F. and watered daily with a sprinkler. About 10 to 14 days after planting when the primary leaves of the bean plant are almost fully expanded and the first trifoliate leaves are just starting to form, the plants are sprayed. The spray is prepared by weighing out 50 mg. of the test compound, dissolving it in 5 ml. of acetone containing 1 percent Tween 20 (polyoxy-ethylene sorbitan monolaurate) and then adding 5 ml. of water. The solution is sprayed on the foliage using an atomizer. The spray concentration is 0.5 percent and the rate would be approximately 20 lb./acre if all of the spray were retained on the plant and soil, but some spray is lost so it is estimated that the application rate is approximately 12.5 lb./acre.

Beans are used to detect defoliants and plant growth regulators. The beans are trimmed to two or three plants per flat by cutting off the excess weaker plants several days before treatment. The treated plants are placed back in the greenhouse and care is taken to avoid sprinkling the treated foliage with water for three days after treatment. Water is applied to the soil by means of a slow stream from a watering hose taking care not to wet the foliage.

Injury rates are recorded 14 days after treatment. The rating system is the same as described above for the preemergence test where (—), (+), (++) and (+++) are used for the different rates of injury and control. The injury symptoms are also recorded. The maximum activity index for complete control of all the species in the post-emergence screening test is 18 which represents the sum of the plus marks obtained with the six plant species used in the test. The herbicide activity indices are shown in table III.

The new compounds of the present invention are used as preemergence or post-emergence herbicides and are applied in a variety of ways at various concentrations. In practice the compounds are formulated with an inert carrier, utilizing methods well known to those skilled in the art, thereby making them suitable for application as dusts, sprays, or drenches and the like, in the form and manner required. The mixtures can be dispersed in water with the aid of a wetting agent or they can be employed in organic liquid compositions, oil and water, water in oil emulsions, with or without the addition of wetting, dispersing or emulsifying agents. The amount applied depends upon the nature of the seeds or plants to be controlled and the rate of application varies from 1 to approximately 50 pounds per acre. One particularly advantageous way of applying the compound is a narrow band along a row crop straddling the row. In practice the compounds are formulated with an inert carrier utilizing methods well known to those skilled in the art, thereby making them suitable for particular application.

The concentration of a compound of the present invention, constituting an effective amount in best mode of administration in the utility disclosed is readily determinable by those skilled in the art. Various changes and modifications are possible without departing from the spirit and scope of the invention described herein and will be apparent to those skilled in the art to which it pertains. It is accordingly intended that the present invention shall only be limited by the scope of the claims.

What is claimed is:

1. A compound corresponding to the formula

in which R_1 and R_2 are independently selected from the group consisting of hydrogen, lower alkyl, allyl and cycloalkyl having from three to six carbon atoms, inclusive; X is selected from the group consisting of fluorine, chlorine, bromine and lower alkyl having from one to four carbon atoms, inclusive; and n is an integer having a value from zero to four, inclusive.

55 2. A compound according to claim 1 in which R_1 is hydrogen, R_2 is lower alkyl and n is 0.

3. A compound according to claim 2 in which R_2 is methyl.

4. A compound according to claim 2 in which R_2 is n-butyl.

5. A compound according to claim 2 in which R_2 is i-propyl.

60 6. A compound according to claim 2 in which R_2 is n-propyl.

7. A compound, according to claim 1 in which R_1 is hydrogen, R_2 is allyl and n is 0.

65 8. A compound according to claim 1 in which R_1 is hydrogen, R_2 is lower alkyl, X is halogen and n is 1 to 4, inclusive.

9. A compound according to claim 8 in which R_2 is methyl, X is chlorine and n is 2.

10. A compound according to claim 1 in which R_1 is hydrogen, R_2 is allyl, X is halogen and n is 1 to 4, inclusive.

70 11. A compound according to claim 10 in which X is chlorine and n is 2.

12. A compound according to claim 1 in which R_1 is hydrogen, R_2 is lower alkyl, X is lower alkyl having one to four carbon atoms inclusive, and n is 1 to 4, inclusive.

75 13. A compound according to claim 1 in which R_1 is hydrogen, R_2 is lower alkyl, X is lower alkyl having one to four carbon atoms inclusive, and n is 1 to 4, inclusive.

13. A compound according to claim 12 in which R₂ is methyl, X is methyl and n is 2.

14. A compound according to claim 12 in which R₂ is n-butyl, X is methyl and n is 2.

15. A compound according to claim 1 in which R₁ is hydrogen, R₂ is cycloalkyl having from three to six carbon atoms inclusive, and n is 0.

16. A compound according to claim 15 in which R₂ is cyclohexyl.

17. A compound according to claim 1 in which R₁ is hydrogen, R₂ is lower alkyl, X is halogen and lower alkyl and n is 2 to 4 inclusive.

18. A compound according to claim 17 in which R₂ is methyl, X is chlorine and methyl, and n is 2.
